UNITED STATES PATENT OFFICE.

RICHARD DALE, OF MOUNT CARROLL, ILLINOIS.

BUILDING CONSTRUCTION.

Application filed March 26, 1923. Serial No. 327,610.

To all whom it may concern:

Be it known that I, RICHARD DALE, a citizen of the United States, residing at Mount Carroll, in the county of Carroll and 5 State of Illinois, have invented certain new and useful Improvements in a Building Construction, of which the following is a specification.

My invention relates to improvements in 10 building construction and more particularly to blocks of cement, concrete or other composition which are especially adapted for use as interlocking sections of box culverts, sewers and building walls.

15 The blocks are preferably made at some central location and transported to the building site where they are assembled either with or without grouting of the interlocking faces. As heretofore constructed, such 20 blocks have had vertical interlocking faces which require that the overlying block be accurately positioned directly above its permanent seat on the underlying blocks in order that it may be finally positioned there- 25 on. This accurate positioning of such blocks requires an expenditure of a consider- able amount of time and painstaking care and also results in the removal and wasting 30 of the grout which may have been plastered on the interlocking surfaces, such wasting being caused by the scraping of the interlocking faces together.

One of the objects of the invention is 35 to provide blocks having interlocking faces adapted for initial engagement with the corresponding faces of the underlying blocks without requiring that the block be first positioned in exact vertical alignment above 40 its permanent position and which after such initial engagement will move by gravity into its permanent position.

Another object is to provide mutually 45 interlocking blocks whose interlocking faces do not come squarely into contact until the blocks reach their permanent position in the structure relative to the blocks already in place.

Another object is the provision of blocks 50 having interlocking faces inclined to the vertical in such a way that moisture will not collect between the blocks and damage the structure by freezing or otherwise.

Another object is to provide interlocking 55 blocks which will break joints with the underlying blocks at substantially any rela-

tive longitudinal position of the overlying and underlying blocks.

Another object is to provide blocks which interlock with the vertically adjacent blocks so that both lateral and longitudinal dis- 60 placement of the blocks is prevented.

Another object is to provide an improved box culvert construction.

Another object is to provide an improved 65 head wall for culverts constructed of blocks which mutually interlock to form the head wall and also interlock with the main wall of the culvert in such a way as to prevent overturning or sliding movement of the head wall relative to the culvert. 70

The foregoing and other objects of the invention will appear in the following detailed description.

Referring to the drawing illustrating the invention, Fig. 1 is an elevational view of 75 box culvert constructed of my improved interlocking blocks. Fig. 2 is an end elevation, on an enlarged scale, of the culvert shown in Fig. 1. Fig. 3 is an enlarged scale detail on the line 3—3 of Fig. 1. Fig. 4 is a perspective view of two longitudinally adjacent lower section blocks of the culvert. Fig. 5 is a perspective view of an upper section block of the culvert showing the complementary 80 interlocking faces adapted for engagement with corresponding faces on the lower section blocks. Figs. 6 and 7 are detail views of an alternative form of complementary interlocking faces. Figs. 8 and 9 are detail views of another alternative form of 85 complementary interlocking faces and Figs. 10 and 11 are detail views of a preferred form of head-wall blocks.

The numeral 10 generally designates a box 90 culvert having head walls 11. The culvert body comprises a plurality of U-shaped blocks 12 of any convenient length and corresponding inverted U-shaped blocks 13 resting upon and arranged to break joints with the blocks 12. The blocks 12 and 13 may be made of any desired width and depth 95 corresponding to the required duty of the culvert in carrying off water.

Each of the blocks 12 and 13 are provided 100 at one end with a tongue 14 and at the other end with a groove 15 into which the tongue of the adjacent block closely fits. These 105 tongues and grooves are semi-circular in section but may well be made of triangular or rectangular section if desired and serve 110

to longitudinally align each of the blocks 12 and 13 with the longitudinally adjacent blocks.

Provision is made for interlocking the blocks 13 with the blocks 12 by forming a series of pyramidal shaped downwardly sloping indentations 16 on the upper faces of the legs of the blocks 12 and corresponding complementary pyramidal shaped projections 17 on the lower faces of the legs of the blocks 13, which fit closely in the indentations 16 when the blocks are in position. The various indentations 16 are identical in shape and size and alternately converge inwardly and outwardly with the adjacent indentations separated by horizontally extending edges 18.

The indentations 16 preferably have a width substantially equal to the thickness 20 of the vertical walls so that the blocks 13 may interlock and break joints with the blocks 12 at spaced intervals substantially equal to the thickness of the vertical walls. This feature is advantageous in that the 25 culvert can be constructed of any desired length by using blocks of standard and special lengths which will break joints at any desired point. In Figure 1 the culvert is shown as constructed of standard length 30 blocks 12 and 13 except at the ends where blocks 13_a and 19 of special lengths are provided.

In placing a block 13 in position on the underlying blocks 12 it is only necessary 35 that the apex of the projections 17 shall be directed at random into the corresponding indentations 16 regardless of whether the blocks are in exact vertical, transverse or longitudinal alignment. The weight of the 40 block will cause it to slide into its final position in exact vertical, transverse and longitudinal alignment with the adjacent blocks already in assembled position. If the interlocking faces of the blocks have been grouted 45 before assembling, the blocks 13 will slide into position without scraping off the grout as is the case if such faces are vertical or otherwise in complete contact as they slide into final position.

50 The sloping faces of the indentations 16 and the projections 17 prevent water from collecting where it will freeze and force the blocks apart and otherwise damage the interlocking sections.

55 The head walls 11 are usually provided for culverts placed deep underground to prevent the fill from sliding down and obstructing the culvert. The head walls are preferably built in two sections 20 and 21 as 60 shown. The upper faces of the section 20 are provided with indentations 16 similar to the indentations in blocks 12 and the lower faces of the section 21 are provided with projections 17 fitting therein so that the sections 20 and 21 mutually interlock. The

head walls are interlocked with the main body of the culvert by providing the lower face of the end block 13_a with projections 17 and the upper horizontal face of the end block 13 with indentations 16 which engage 70 and interlock with corresponding complementary faces formed in offsets 22 and 23 in the head wall sections 20 and 21 respectively. The head wall sections 20 and 21 are preferably joined below the middle of 75 the culvert in order that the section 21 may most effectively resist the pressure of the fill which tends to overturn the head wall.

While I have shown blocks angular in section, it is to be understood that my interlocking sections are equally as well adapted 80 for use on blocks having a circular or other desired cross sections.

The projections 24 of Fig. 7 and the complementary indentations 23 of Fig. 6 illustrate alternative interlocking sections which differ from the preferred form by providing rounded fillets 27 on the projections 24. These fillets terminate in horizontal lines 28 and have corresponding complementary 90 fillets 25 and surfaces 26 on the indentations 23.

The alternative construction illustrated in Figs. 8 and 9 differ from the preferred form by providing a relatively narrow horizontal 95 surface 29 between adjacent pyramidal indentations 30 and a downwardly extending surface 31 which connects the sloping sides 32 and 33 bounding the indentations. Corresponding surfaces 34 and 35 on the projections 36 are complementary to the surfaces 29 and 31 respectively.

Thus it will be seen that I have provided blocks which are capable of being assembled 105 into a culvert or other structure and of being so interlocked together as to form a structure which will remain in alignment and resist all the forces which ordinarily tend to wreck or destroy such constructions.

I claim:

1. An oblong block having one of its horizontal faces comprising a plurality of triangular surfaces arranged so that a pair of adjacent triangular surfaces incline downwardly to one side of the block and intersect in a line lying in a plane perpendicular to the axis of the block, and an adjoining pair of triangular surfaces which incline downwardly to the other side of the block and intersect in a line lying in a plane perpendicular to the axis of the block with the adjacent triangular surfaces of adjoining pairs intersecting in a horizontal line which is inclined to the longitudinal axis of the block.

2. In a concrete box culvert, the combination with a plurality of complementary U-shaped blocks forming the body of the culvert, of a head wall having a lower section interlocking with the outside bottom

face and the outer face of the side walls of the culvert, and an upper section having interlocking engagement with said lower section and with the outside top face and the outer face of the side walls of the culvert.

3. Culverts formed of blocks having interlocking faces lying in planes inclined to horizontal and vertical planes and to horizontal lines perpendicular to the longitudinal axis of the culvert.

4. A block of the class described having one of its faces adapted for interlocking engagement with a complementary face of a corresponding block, said face being bound-

ed by planes inclined to vertical and horizontal planes and to lines transverse to the length of the block.

5. Complementary blocks of the class described having interlocking faces, the faces of one of said blocks having projections adapted to engage corresponding indentations in the other block, said projections and indentations being bounded by planes inclined to vertical, and horizontal planes and to horizontal lines perpendicular to the longitudinal axis of the block.

RICHARD DALE.
